(57) **CLAIM**

The ornamental design for a display screen or a portion thereof with animated graphical user interface, as shown and described.

DESCRIPTION

FIG. 1 is a front view of a display screen or portion thereof with animated graphical user interface.

FIG. 2 is a second image thereof;

FIG. 3 is a third image thereof;

FIG. 4 is a forth image thereof;

FIG. 5 is a fifth image thereof;

FIG. 6 is a sixth image thereof;

FIG. 7 is a seventh image thereof;

FIG. 8 is a eighth image thereof;

FIG. 9 is a ninth image thereof;

FIG. 10 is a tenth image thereof;

FIG. 11 is a eleventh image thereof; and,

FIG. 12 is a twelfth image thereof.

The appearance of the animated graphical user interface sequentially transitions between the images shown in FIGS. 1-12. The process or period in which one image transitions to another forms no part of the claimed design. The dot-dash lines showing a display screen or portion thereof form no part of the claimed design. The broken lines showing graphical elements within the display screen form no part of the claimed design.
